UNITED STATES PATENT OFFICE

JAMES DUNCAN, OF WATERVILLE, CONNECTICUT, ASSIGNOR TO SCOVILL MANUFACTURING COMPANY, OF WATERBURY, CONNECTICUT, A CORPORATION OF CONNECTICUT

DESIGN FOR A LAVATORY AND SHOWER VALVE HANDLE

Application filed June 4, 1932. Serial No. 43,984. Term of patent 7 years.

To all whom it may concern:

Be it known that I, JAMES DUNCAN, a citizen of the United States, residing at Waterville, in the county of New Haven and State of Connecticut, have invented a new, original, and ornamental Design for Lavatory and Shower Valve Handles, of which the following is a specification, reference being had to the accompanying drawing, forming part thereof.

Fig. 1 is a perspective view of a lavatory

and shower valve handle, showing my new design.

Fig. 2 is a top plan view.

Fig. 3 is a side elevation.

I claim:

The ornamental design for a lavatory and shower valve handle as shown.

In testimony whereof, I have affixed my signature to this specification.

JAMES DUNCAN.
